ROCKWELL CHAPMAN, OF BUCHANAN, MICHIGAN.

Letters Patent No. 72,454, dated December 24, 1867.

IMPROVEMENT IN WATER-WHEELS.

The Schedule referred to in these Letters Patent and making part of the same.

TO ALL WHOM IT MAY CONCERN:

Be it known that I, ROCKWELL CHAPMAN, of Buchanan, in the county of Berrien, and State of Michigan, have invented certain new and useful Improvements in Water-Wheels; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention consists in a novel manner of constructing a water-wheel, as hereinafter described.

Figure 1 is a front elevation, and

Figure 2 a side plan view.

My present invention relates to certain improvements in that class of wheels denominated re-action wheels, and in its general construction resembles the wheel on which a patent was recently granted to me.

To construct my improved wheel, I first make a circular hub, A, having the main portion of the wheel projecting radially therefrom a distance equal to the depth that it is intended to have the buckets, as represented by B. I then form buckets therein by cutting vertically from the surface toward the centre, the outer face of the bucket extending half way across the face of the portion B, the cut or face of the bucket growing gradually narrower as it extends inward toward the hub A, its inner line forming an angle of about forty-five degrees to the outer side of the wheel, and running entirely out to the side as it arrives at the line of the hub, as shown in fig. 2, the inner side of the cut being curved and inclined, as represented. To the sides of the projecting part B of the wheel, metal plates, l, are then attached, said plates being of such a size as to reach from one of the buckets a, past the next bucket, and half way to the third. These plates are curved laterally along their centre, so that when lapped one over the other, as they necessarily are, when applied to the sides of B, the curved portions form a channel for the escape of the water, the line of the channel thus formed being indicated by the lines m and n of fig. 1, the mouth of the channel terminating on the outside at e, and extending back to the bucket a. The buckets are so formed in the part B as to alternate, those on one side standing intermediate between those on the opposite side, as shown clearly in fig. 2. The wheel when thus formed is enclosed in a case having openings in the sides corresponding with the size of the part B, said case fitting close around the edge of the plates l on each edge of B. The water entering the case, strikes against the vertical face of the buckets a, and after expending its force against the bucket, escapes thence through the channel between the plates l, escaping at the mouth e outside of the case.

Having thus described my invention, what I claim, is—

A water-wheel consisting of the radially-projecting hub B, having the buckets a formed therein alternately on opposite sides, each bucket extending half way across the face of B, as shown in fig. 2, and having the discharge-passages formed on the sides by the overlapping plates l, applied as described.

ROCKWELL ^{his} X CHAPMAN.
